UNITED STATES PATENT OFFICE.

ALEXANDER BOGDÁNFFY, OF NEW YORK, N. Y., ASSIGNOR TO THE INTERNATIONAL CORK COMPANY, OF BROOKLYN, NEW YORK, A CORPORATION OF NEW YORK.

CORK-DOCKING MACHINE.

1,099,686.

Specification of Letters Patent.

Patented June 9, 1914.

Application filed August 29, 1912 Serial No. 717,753.

To all whom it may concern:

Be it known that I, ALEXANDER BOGDÁNFFY, a subject of the King of Hungary, and resident of the city of New York, in the county of Kings and State of New York, have invented certain new and useful Improvements in Cork-Docking Machines, of which the following is a specification.

The present invention relates to cork docking machines, or more particularly to an apparatus for reducing the cork to its proper size and finishing the ends thereof.

One of the objects of the invention is to provide a simple and efficient device of this type, whereby, in a continuous operation, the corks are reduced to their proper sizes and both ends of the same are finished simultaneously.

Another object of the invention is to produce a novel and improved work-holder which rotates continuously, and is adapted to receive the corks and to present them in their proper positions to the cutting and finishing means.

A further object of the invention is to provide a simple feeding device which delivers the corks to the work-holder, and which is actuated by and moves in unison with said work-holder.

With these and other objects in view, which will more fully appear as the nature of the invention is better understood, the same consists in the combination, arrangement and construction of parts hereinafter fully described, pointed out in the appended claims and illustrated in the accompanying drawings, it being understood that many changes may be made in the size and proportion of the several parts and minor details of construction within the scope of the appended claims without departing from the spirit or sacrificing any of the advantages of the invention.

One of the many possible embodiments of the invention is illustrated in the accompanying drawings, in which:

Figure 1 is a plan view of a machine constructed in accordance with the present invention; Fig. 2 is a front elevation of the same; Fig. 3 is a plan view of the work-holder; Fig. 4 is a section taken on line 4-4 of Fig. 3; Fig. 5 is a sectional view of the cutting means; Fig. 6 is a sectional view of the finishing or grinding means; Fig. 7 is a front elevation of the feeding means;

Fig. 8 is a plan view of the feeding means; Fig. 9 is a front elevation of a detail of the feeding means; Fig. 10 is a plan view of the detail shown in Fig. 9; Fig. 11 is a bottom plan view of a detail of the work-holder; Fig. 12 is a plan view of a belt tightening means used in connection with the cutting means of the machine; and Fig. 13 is a section taken on line 13-13 of Fig. 12.

In the drawings, the numeral 20 indicates the frame of the apparatus, comprising a casing-like structure, having apertured side walls which support a horizontal frame plate 21. In this frame plate is rotatably mounted a vertical shaft 22, carrying upon its upper end the work-holder 23 hereinafter to be described. The lower end of the shaft 22 is supported in a step-bearing 24, through the box of which extends a set screw 25, adapted to lower or raise the shaft 22 and the parts carried thereby. To the shaft 22 is attached above the frame plate 21 a spider-like block 26, to which is secured by means of screws 27, or otherwise, a horizontal disk 28 a substantial distance above the frame plate 21. The disk, forming the base plate of the work-holder, is provided with a central circular opening 29, and with a plurality of arc-shaped slots 30 near its peripheral portion. In each of the slots 30 is arranged a stationary jaw 31 and a movable jaw 32, the latter being attached to or, preferably, made integral with an arm 33, which is pivoted at 34 in any suitable manner to the underside of the disk 28. The pivot of each arm 33 comprises, preferably, a bolt 35, having an extension 36 projecting toward the frame plate 21, and around this extension is coiled a spring 37, one end of which is secured to the extension 36, while its other end is fastened to the arm 33, and tends thus to hold the movable jaw 32 against the stationary jaw 31. The stationary jaws are provided with notches 38 and the movable jaws with notches 39, which register, when the movable jaws contact with the stationary jaws, forming thereby apertures in which the corks are adapted to be seated. The ends of the arms 33 project toward the axis of the shaft 22, and are adapted to be acted upon by a cam 40, which is arranged in the opening 29 in the disk 28. The cam is provided with an upwardly extending sleeve 41, drawn over the reduced portion 42 of the shaft 22. The upper end of the sleeve is 110

screw-threaded, as shown at 43, these threads being in mesh with those of nuts 44 and 45, the nut 44 being attached to an arm 46, which is held between stops 47, 47 upon the frame plate 21. The purpose of the arm 46 and the stops 47, coöperating therewith, is to hold the cam 40 in the proper position relative to the arms 33 upon the work-holder. The upper end of the shaft 42 is also screw-threaded, as shown at 48, and these screw threads mesh with a nut 49. If the nuts 49, 45 and 44 are loosened, the cam can be shifted around the axis of the shaft 42 to vary and predetermine the points at which the movable jaws will open and close.

The means for feeding the corks to the work-holder comprises a bracket 50, the base 51 of which is attached to the frame plate 21. In this bracket is shiftably mounted a vertical feeding tube 52, having a flaring mouth 53. Into this feeding tube, which is adapted to be lowered into the slots 30 as they pass under the same, are placed by hand or fed through a chute the corks to be docked and finished. The corks are fed onto an arc-shaped support 54, which is adjustably held on the bracket 50 by means of a set screw 55, engaging the support and a vertical slot 56 in the bracket. The support 54 is arranged below the disk 28, and its distance from the frame plate 21 can be varied. The purpose of this arrangement will be hereinafter explained. The means for lowering the feeding tube 52 into the slots 30 in the disk 28 and for withdrawing the same from said slots comprises a lever 57, which is fulcrumed at 57' to the bracket 50, said lever having a notch 57'', in which is seated a pin 52', carried by the feeding tube 52. The free end of the lever 57 carries a roller 58, which is arranged in the path of a plurality of cams 61 upon a ring 62, the latter being fastened to the upper face of the disk 28. In order to permit of an adjustment of the cams relative to the roller 58, the ring 62 is provided with slots 63 in engagement with set screws 64, which fasten the said ring to the disk 28. To the bracket 50 is furthermore pivoted at 65 a swinging lever 66, having a cam-shaped recess 67 in its rear face, in which is seated a pin 68, the latter being adjustably mounted upon the lever 57. To the lower end of the swinging lever 66 is adjustably fastened by means of a set screw 69 a finger 70, which is adapted to project through a slot 71 into the feeding tube 52. A spring 72, attached to the bracket 50 and the swinging lever 66, tends to withdraw the finger 70 from the tube 52. The cams 61 are arranged in such a manner relative to the slots 30 in the disks 28 that, whenever a slot arrives into registering position relative to the feeding tube 52 (in which position the movable jaw 32 in said slot does

the roller 58 is lowered into a recess in the cam ring 62 by its own weight and that of the feeding tube 52. In this position the finger 70 is withdrawn by the spring 72 from the feeding tube, whereby a cork will be deposited into the arc-shaped slot to rest on the support 54. In the further rotation of the disk 28, the roller 58 is forced upward by one of the cams 61, withdrawing thereby the tube 52 from the arc-shaped slot 30. At the same time the pin 68 forces the swinging lever 66, against the action of the spring 72, toward the tube 52, or in other words it causes the finger 70 to project into the tube 52 and to prevent thus the next cork in said tube from being fed onto the support 54. When the next slot in the series arrives into registering position relative to the tube 52, the said tube is again lowered and the operation now described is repeated. After the cork is deposited into one of the slots 30, the movable jaw is gradually disengaged from the cam 40, whereby the said jaw will move under the action of its spring 37 toward the stationary jaw, which will, in coöperation with the movable jaw, grip the cork and present it to the cutting means.

The cutting means comprises a disk cutter 73, which is attached to a shaft 74, the upper end of which is rotatably mounted in a block 75, which is carried by a bracket 76, provided upon its lower end with a step-bearing 77, in which is journaled the lower end of the shaft 74. A set screw 78 serves to raise or lower the disk cutter 73 to permit the cork to be cut at the proper place, or in other words to reduce the cork to a predetermined size. The disk cutter rotates above the disk 28 of the work-holder, so that by setting the support 54 or the disk cutter 73, the size of the cork can be easily predetermined. As the disk cutter must be sharpened from time to time, and its diameter thus naturally reduced, means must be provided for shifting the shaft 74 and the cutter carried thereby toward the work-holder shaft 22. For this purpose the bracket 76 is shiftably arranged upon the frame 20; the means for shifting the same comprising a screw threaded spindle 79 meshing with threads in lugs 80, 80 upon the frame of the machine, said spindle being rotatably carried by the bracket 76 and having at its outer end a hand wheel 81.

After the cutting operation has been performed, the corks are presented by the work-holder to the grinding means. The grinding means comprises two parallel horizontal grinding disks 82 and 83, for instance emery disks. The disk 82 is attached to a vertical shaft 84, which is journaled in the frame plate 21, its lower end being supported in a step-bearing 85, which is provided with a set screw 86 for a well known

purpose. The disk 82 has an upwardly extending screw threaded sleeve 87, over which fits a screw threaded sleeve 88, which carries the disk 83. A locking nut 89 meshes with the threads 90 upon the upper end of the shaft 84. It will be observed that the distance between the disks 82 and 83 may be varied, at will. The disks 82 and 83 are arranged on opposite sides of the work-holder. The peripheral portions of the disks 82 and 83 are slightly tapered, as shown at 91 and 92, respectively, whereby the corks will be ground down gradually to their proper sizes.

The main driving shaft 93 of the machine is journaled in bearings 94, 94. Upon this shaft is mounted a loose pulley 95 and a fixed pulley 96, by the intermediary of which rotation is imparted to the shaft. A belt 97 running over pulleys 98 and 99 upon the driving shaft 93 and the shaft 84, respectively, transmits rotation to the shaft 84 and thus to the grinding disks 82 and 83. Rotation is imparted to the shaft 74 of the cutter by a belt 100, running over pulleys 101 and 102 upon the driving shaft and the shaft 74, respectively. A pulley 103 is keyed to the shaft 74, and over this pulley runs a belt 104 in engagement with a pulley 105 upon the shaft 22 of the work-holder. As, however, the distance between the shafts 74 and 22 is to be varied as above described, obviously a belt tightener or stretcher must be provided. This belt tightener comprises two plates 106, 106, which are fulcrumed at 107, 107 to the frame plate 21. Each of the plates 106 carries two rollers 108, 108, which engage opposite sides of the belt 104. Links 109, 109 are pivoted at 110 to the block 75 and at 111, 111 to the roller carrying plates 106. A shifting of the block 75 will result in a swinging of the roller carrying plates 106 around their pivots 107, causing thereby a tightening of the belt 104.

The operation of the machine is as follows: According to the length of the corks to be finished, some of the parts of the machine must be set. More particularly the support 54 is shifted, the cutter 73 must be shifted by means of the set screw 78 to a proper distance from the upper face of the support 54; the distance between the grinding disks 82 and 83 must be set to correspond to the length of the corks, and furthermore the shaft 84 shifted to bring the grinding disks into proper relation to the work-holder disk 28. The corks are placed into the feeding tube 52. When now rotation is imparted to the main driving shaft of the apparatus, the cam 40 will cause the swinging jaws 32 to swing around their pivots away from their coacting stationary jaws a suitable distance before a slot 30 arrives into registering position with the feeding tube. When a slot arrives at this

point, the jaws are fully separated. The feeding tube 52 is lowered in a manner above described into the slot, and the finger 70 withdrawn from the tube, whereby a cork will be deposited onto the support 54. In the further rotation of the work-holder, the feeding tube 52 is withdrawn from the slot and the cork moved by the stationary jaw in the slot along the arc-shaped support 54 until it is gripped by the two coöperating jaws in said slot. In this manner it is conveyed to the rotary cutter 73, which reduces the cork to its proper length by slicing off a cork disk from its upper end. The cork is then brought by the closed jaws between the emery disks which will simultaneously grind or finish both ends of the same. In the further rotation of the work-holder, the jaws separate, releasing the cork when it arrives above an aperture 112 in the frame plate 21, through which it drops into a chute 113, to be delivered thereby into a receptacle located under said chute. The jaws remain open, and, when they arrive again opposite the feeding tube, the operation now described is repeated.

It is obvious that, while herein the operation of one pair of jaws has been described, the others act in the same manner, so that a continuous operation is obtained. The grinding disks and the cutter rotate at a higher rate of speed than the work-holder.

It is to be observed that instead of the work-holder herein described, any other endless conveyer construction can be used within the scope of the appended claims.

What I claim is:—

1. In a cork finishing machine, the combination with a frame, of a rotary horizontal disk mounted thereon having arc-shaped slots, a stationary gripping jaw in each slot, a feeding tube shiftably arranged upon said frame having an aperture at or near its end, a finger adapted to project into said tube through said aperture, means for lowering said tube into the slots in said disk when a slot arrives into registering position with said tube and simultaneously withdrawing said finger from said tube, whereby a cork is fed into said slot, said last named means serving to withdraw said tube from said slots and to project said finger into said tube, a movable jaw in each slot adapted to coact with said stationary jaws to hold corks in said slots so as to project beyond both faces of said disk, means for predetermining the distance to which one end of each cork projects beyond one of the faces of said disk, cutting means acting upon the opposite ends of the corks, and grinding disks on opposite faces of said first-named disk adapted to act upon both ends of the corks simultaneously.

2. In a cork finishing machine, the combination with a frame, of a rotary horizontal

- disk mounted thereon having arc-shaped slots, a stationary gripping jaw in each slot, a feeding tube shiftably arranged upon said frame having an aperture at or near its end, 5 a finger adapted to project into said tube through said aperture, means for lowering said tube into the slots in said disk when a slot arrives into registering position with said tube and simultaneously withdrawing 10 said finger from said tube, whereby a cork is fed into said slot, said last-named means serving to withdraw said tube from said slots and to project said finger into said tube, a movable jaw in each slot adapted to coact 15 with said stationary jaws to hold corks in said slots so as to project beyond both faces of said disk, and grinding disks on opposite faces of said first named disk adapted to act upon both ends of the corks simultaneously. 20 3. In a cork finishing machine, the combination with a rotary horizontal disk having arc-shaped slots, of a stationary gripping jaw in each slot, a stationary guide arranged below said disk in the path of said 25 slots, a movable jaw in each slot adapted to coact with said stationary jaws to hold corks in said slots so as to project beyond both faces of said disk, and means disposed above said disk in registering position with said 30 stationary guide for feeding a cork in upright position into a slot when it arrives above said guide, the latter serving to predetermine the distance to which one end of each cork projects beyond the lower face of 35 said disk. 4. In a cork finishing machine, the combination with a rotary horizontal disk having arc-shaped slots, of a stationary gripping jaw in each slot, a stationary guide arranged below said disk in the path of said 40 slots, a movable jaw in each slot adapted to coact with said stationary jaws to hold corks in said slots so as to project beyond both faces of said disk, a feeding tube for corks in registering position with said stationary guide, and means connected with said tube, whereby a cork is placed in upright position onto said guide through a slot when the latter arrives in registering position with said 45 guide, the latter serving to predetermine the distance to which one end of each cork projects beyond the lower face of said disk. 5. In a cork finishing machine, the combination with a horizontal continuously rotating disk having arc-shaped slots, of a stationary gripping jaw in each slot, a movable jaw in each slot adapted to coact with said stationary jaws to hold corks in said slots so as to project beyond both faces of said disk, a stationary guide for predetermining the distance to which one end of each cork projects beyond one of the faces of said disk, and means for feeding a cork through a slot onto said guide when a slot arrives in registering position with said guide. 6. In a cork finishing machine, the combination with a horizontal continuously rotating disk having arc-shaped slots, of a stationary gripping jaw in each slot, a movable jaw in each slot adapted to coact with said stationary jaws to hold corks in said slots so as to project beyond both faces of said disk, a stationary guide for predetermining the distance to which one end of each cork projects beyond one of the faces of said disk, and a feeding tube disposed above said disk in registering position with said guide, whereby a cork is fed through a slot onto said guide when a slot arrives in alignment with said tube. 7. Signed at New York, in the county of Kings and State of New York, this 1st day of August, A. D. 1912.
